US00D969129S

(12) **United States Design Patent** (10) Patent No.: **US D969,129 S**
Kayama et al. (45) Date of Patent: ** Nov. 8, 2022

(54) **AUTHENTICATION DEVICE**

(71) Applicant: **NEC Platforms, Ltd.**, Kawasaki (JP)

(72) Inventors: **Katsumi Kayama**, Kawasaki (JP);
Tomohiro Uchida, Kawasaki (JP);
Shuji Yamaguchi, Kawasaki (JP);
Naoki Kato, Kawasaki (JP)

(73) Assignee: **NEC PLATFORMS, LTD.**, Kawasaki (JP)

(**) Term: **15 Years**

(21) Appl. No.: **29/736,242**

(22) Filed: **May 28, 2020**

(30) **Foreign Application Priority Data**

Nov. 29, 2019 (JP) 2019-026600

CLAIM

The ornamental design for an authentication device, as shown and described.

DESCRIPTION

FIG. 1 is a front, left side, top perspective view of an authentication device showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a rear, right side, top perspective view thereof; and,

(Continued)

FIG. 9 is a cross-sectional view thereof, taken in the direction of line 9-9 of FIG. 3.

1 Claim, 8 Drawing Sheets
